Patented Nov. 21, 1922.

Inventor

Kurt M. Geisler

UNITED STATES PATENT OFFICE.

KURT M. GEISLER, OF HACKENSACK, NEW JERSEY.

ELECTRICAL ENGINE.

Application filed November 19, 1920. Serial No. 425,113.

To all whom it may concern:

Be it known that I, KURT M. GEISLER, a citizen of the United States, residing at Hackensack, in the county of Bergen and State of New Jersey, have invented certain new and useful Improvements in an Electrical Engine, of which the following is a specification.

My invention relates to an electrical engine, of the reciprocatory type, embodying a plurality of piston-cores.

An important object of the invention is to provide an engine of the above mentioned character, which when cranked or started, automatically makes and breaks the several circuits for the solenoid windings.

In the accompanying drawings forming a part of this specification, and in which like numerals are employed to designate like parts throughout the same,

Figure 1 is a central vertical longitudinal section, of an engine embodying my invention,

Figure 2 is a transverse section taken on line 2—2 of Figure 1,

Figure 3 is a detail section through one of the spring thrust contacts.

In the drawings, the numeral 5 designates preferably vertically arranged cylinders, carried by a crank-case 6. This crank-case has bearings 7, receiving crank shaft 8, having pairs of cranks 9, 9' and 10, 10', as shown. Mounted to reciprocate within the cylinders are pairs of piston-cores 12, 12' and 13, 13', connected with connecting rods 14, pivoted to the cranks.

Surrounding the cylinders containing the pistons 12, 12' are solenoid windings 15 and 15', while solenoid windings 16 and 16', surround the other cylinders.

The wire 17 may be connected with the positive pole of a source of current, and wire 18 with the opposite pole. The wire 18 has connection with wires 19 and 20, connected with solenoid windings 15 and 16, and also has connection with wires 21 and 22, connected with solenoid windings 15' and 16'.

An insulating strip 23 is arranged upon the top of the cylinders and secured thereto. Casings or tubes 24 extend through openings in this strip, there being a pair of tubes for each cylinder. Reciprocatory contacts 25, slide in the tubes 24, and are moved downwardly by springs 26. The downward

movement of the contact is limited by a transverse pin 27, carried thereby, operating in slots 28.

The wire 17 has electrical connection with wires 29 and 29', connected with the outer contacts 25 of the cylinders within the windings 15 and 16. The wire 17 also has electrical connection with wires 30 and 35, electrically connected with the contacts 25 of the cylinders within the solenoid windings 15' and 16'. The contact 25 of the cylinder 60 within the winding 15 is connected with a wire 31, connected with one end of the winding 15'. The contact 25 of the cylinder within the winding 15 is connected with a wire 32, connected with one end of the winding 70 15. The contact 25 within the cylinder of winding 16' is connected with wire 33, connected with one end of the winding 16. One end of the winding 16' is connected with wire 34, connected with the contact 25 in 75 cylinder 5 of winding 16.

The operation of the pair of piston-cores 12 and 12' is as follows:

When the crank-shaft 8 is turned or cranked in starting the engine, the piston core 12' will be elevated, as shown in Figure 1, and engage contacts 25, closing a circuit to energize solenoid winding 15. In this closed circuit current will flow from wire 17, through wire 30, one contact 25, wire 32, contact strip 25', the other contact 25, wire 32, solenoid winding 15, and through wire 19 to the wire 18. The winding 15 now becomes energized, and will draw the piston-core 12 upwardly therein, the winding 15 being deenergized when the piston-core 12 descends sufficiently to break contact with contacts 25. When the piston-core 12 reaches its uppermost position, it will engage the two contacts 25, and the winding 15' will be 90 in a closed circuit and hence energized. In this closed circuit current flows from the wire 17, through wire 29, one contact 25, contact strip 25', the other contact 25, wire 31, winding 15', and wire 21 back to the 100 wire 18. The operation of the circuits for the windings 16' and 16 are identical and it is thought unnecessary to describe the same.

It is to be understood that the form of my invention herewith shown and described is 105 to be taken as a preferred example of the same, and that various changes in the shape, size, and arrangement of parts may be re-

sorted to without departing from the spirit of my invention, or to the scope of the subjoined claim.

Having thus described my invention, I

5 claim:

In an electrical engine of the character described, a plurality of cylinders, a solenoid winding surrounding each cylinder, a piston-core sliding in each cylinder, a crank shaft,

10 a connecting rod between each piston-core and crank shaft, a circuit connected with

each solenoid winding and embodying a pair of contacts arranged at the upper end of the cylinder of the other piston-core to be engaged thereby, and a contact strip carried by each piston-core.

In testimony whereof, I have affixed my signature in the presence of two witnesses.

KURT M. GEISLER.

Witnesses:

ALBERT BREY,
PAUL GEISLER.
